UNITED STATES PATENT OFFICE.

LOUIS J. MELIND, OF CHICAGO, ILLINOIS.

TIME-STAMP.

1,355,989.

Specification of Letters Patent. Patented Oct. 19, 1920.

Application filed August 5, 1918. Serial No. 248,275.

To all whom it may concern:

Be it known that I, LOUIS J. MELIND, a citizen of the United States, residing at Chicago, in the county of Cook and State of Illinois, have invented a certain new and useful Improvement in Time-Stamp, of which the following is a full, clear, concise, and exact description, reference being had to the accompanying drawings, forming a part 10 of this specification.

My invention relates to improvements in rubber stamps and has special reference to recording time stamps.

By means of my invention I provide a 15 time recorder which is of the simplest possible nature, the essential parts being a stamping dial and indicator capable of being set by hand to indicate any particular time or hour, and associated therewith a changeable date stamp for recording the day and 20 the month.

These essential features are associated together in a small, light, cheaply constructed and durable hand stamp and one which can 25 be manufactured at a low cost.

The stamp in which I have embodied my invention is particularly adapted for office use for recording on letters, legal papers and any other articles, their time of receipt, etc.

My invention will be more readily understood by reference to the accompanying drawings, forming part of this specification, and in which I have illustrated a preferred 35 embodiment thereof.

Figure 1 is a bottom plan view of the preferred form of my improved time recording stamp;

Fig. 2 is a side elevation of same; 40 Fig. 3 is a vertical central sectional view of the stamp on the line 3—3 of Fig. 1;

Fig. 4 is a view similar to Fig. 1, some of the parts having been removed;

Fig. 5 is an enlarged vertical section on 45 the line 5—5 of Fig. 4;

Fig. 6 is a side elevation of the plate which carries the several stamps; and

Fig. 7 is a vertical section of the stamp plate on the line 7—7 of Fig. 6.

50 In the form in which I prefer to embody my invention, I provide a hollow boxlike

rectangular casing 10, having sides 11 and a top 12 and open at its bottom for the reception of the stamping mechanism.

Within this box I provide an annular 55 shoulder 13 raised above the lower edge of the casing. The shoulder is formed by the edges of two U-shaped sheet metal filler members 14 which together form a lining extending around the inner periphery of the 60 casing and formed to fit snugly therein.

Upon this peripheral shoulder I mount a stamp plate 15, this plate fits nicely within the casing 10 and rests at its periphery upon the shoulder 13. I secure the plate in position by two screws 16 at the middle portion of the plate providing posts 17 secured in the top of the casing and equal in height to the height of the shoulder 13 and adapted to receive the screws. 70

I arrange the shoulder 13 at a suitable distance above the lower edge of the casing to provide a rim 18 of a suitable depth to contain a rubber stamping pad 19. I arrange a small circular pad 20 at the center 75 of the plate 15 providing a shallow metallic cup 21 for carrying same. The cup is mounted for rotation on the plate 15 by a central rivet-like stud 22 upon the upper end of which and above the plate 15, I provide a small bevel gear 23. This pad 20 rotates with the cup in which it is mounted, and I provide an indicator arrow 24 on its face, as best shown in Fig. 1, to stamp an arrow on the article upon which the stamp 85 is used. Upon the impression surface of the pad 19 I provide a circular dial 25 surrounding the circular pad 20 and arranged to indicate the hours from one to twelve having divisions 26 indicating ten minutes for each 90 division, so that the arrow can be set in relation to the dial to indicate very closely to the exact time. For rotating the indicator pad I provide a shaft 27 mounted at its ends in the walls of the casing 10 above the plate 95 15 and extending across the middle of the casing. One end 28 of this shaft is reduced as best shown in Fig. 4, and I provide a hole in the wall of the casing and the filler 14 to receive this reduced end. The opposite 100 end of the shaft extends through the opposite wall of the casing and I provide a finger

5 knob 29 knurled on its outer periphery for turning the shaft. I provide a small bevel gear 30 on the shaft 27 adapted to mesh with the similar gear 23 on the pad cup 21 to turn the cup, and consequently the central pad 20 with its indicating arrow 24 will be rotated when the shaft 27 is rotated.

10 For the purpose of conveniently setting the indicator to any particular position, I provide a duplicate of a dial 25 upon the outer surface of the casing at 31 surrounding the shaft 27, except that this dial 31 is not reversed as is the stamping dial 25, and I provide an indicator finger 32 forming 15 part of the finger knob 29 and fixed to the shaft 27. I arrange the two indicators 31 and 24 and their respective dials to accurately register with each other.

20 Between the central indicator pad and the forward side of the casing I provide a fixed elongated boxlike member 33 to receive and hold rubber type members 33' for indicating the day of the month. These type members fit snugly within the boxlike member 33 and 25 can be readily changed from day to day in a well known manner. In order to secure the member 33 in place without providing any obstruction upon the lower face of the plate 15 outside the area of the member 33, 30 I slot the plate to receive the member 33, and I provide its bottom with end flanges 34 which I rivet to the top side of the plate 15, as best shown in Figs. 6 and 7. The pad 19 fills all the space within the casing not 35 occupied by the central pad and the date pad and can obviously carry such printed matter, as instructions for use or advertising matter, as may be desired.

40 In order that the user shall be sure to properly impress the stamp and thus obtain an even impression over the whole area thereof, I provide a flexible handle so that even if the pad be held at a slight angle to the impression surface, the force used to 45 cause or imprint the impression will cause the stamp to automatically adjust itself evenly upon the impression surface.

50 This handle consists of a rubber stem 35 secured to the casing by a screw 36, the head of the screw being welded or otherwise rigidly secured in the top plate of the casing. To prevent the screw splitting the rubber stem I provide a ferrule 37 surrounding the lower end thereof.

55 For convenience in grasping the rubber stem for use I provide an enlarged wooden ball-like handle 38 having a central opening 39 in its lower end to receive the rubber stem. Preferably I provide a metallic lining 40 for the hole 39 which prevents the splitting of the wood handle and accurately fits the rubber stem. I preferably leave the rubber stem free to slide in the handle so as to give a cushioning effect to the impression stroke, as well as the sidewise

yielding of the handle already described. To prevent the easy removal of the rubber stem from the tube I preferably provide the tube with an integral bottom 41' so that considerable suction will be developed when it 70 is attempted to remove the wooden handle from the stamp.

To yieldingly retain the shaft 27 with the indicating arrow at its adjusted position, I provide a spring bridge 41 arranged with 75 in the casing 10 above the shaft and adjacent to the front wall of the casing. I form the bridge with a V-shaped notch 42 at the middle portion to receive the shaft 27 and I bend the ends 43 on inclines, providing the extreme ends with flat foot portions 44 for contact with the top of the box. The height of the bridge is such that it can be sprung between the shaft and the top of the box and when so positioned will 80 engage the shaft with sufficient friction to prevent any but intentional rotation of the shaft, and will not prevent the shaft being easily turned by means of the finger knob 29. 90

It is obvious that having developed the preferred form of my invention, many other embodiments will readily suggest themselves to one skilled in the art, and I therefore do not confine or limit my invention 95 to the specific structures herein shown and described.

I claim:

1. In a device of the kind described, a casing, a rotatable indicating stamp, a dial 100 stamp surrounding the indicating stamp, a shaft projected through the casing and geared to the rotatable stamp for rotating the same, a similar dial on the outer surface of the casing surrounding the shaft, 105 and an indicator carried by the shaft, said two indicators being arranged to coincide in relation to their respective dials.

2. In a hand stamp the combination of a casing having an open side, a plate removably fixed within said casing parallel to said open side, a dial stamp mounted on said plate and between the peripheral walls of said casing, an indicating stamp rotatably mounted on said plate, a shaft mounted in 110 said casing for adjusting said indicating stamp, and separable gearing between said shaft and indicating stamp.

3. In a device of the kind described, a rotatable indicating stamp, a rotatable shaft 115 for rotating the stamp, a casing in which the apparatus is inclosed, a spring bridge member yieldingly engaged between the shaft and the casing for frictionally preventing the free rotation of said shaft.

4. In a device of the character described, a metallic casing having sides and a top and an open bottom, filler liners in the casing providing a shoulder raised above the open bottom, a pad plate mounted on said 13

filler, a rotatable cup carried by said plate, and adapted to contain an indicating stamp, the cup mounted on a stem projecting through the plate, a bevel pinion on the 5 upper end of the stem, a shaft rotatably mounted in the casing, a bevel pinion on the shaft meshing with the first bevel pinion

for rotating the cup, a dial on the outside of the casing surrounding the shaft, and an indicator carried by the shaft for visually 10 showing the position of the cup.

In witness whereof I hereunto subscribe my name this 30th day of July, A. D. 1917.

LOUIS J. MELIND.
